UNITED STATES PATENT OFFICE.

DAISY DEARMAN, OF PARIS, FRANCE.

DESIGN FOR A BOX OR SIMILAR ARTICLE.

Application filed March 28, 1924. Serial No. 9,087. Term of patent 7 years.

To all whom it may concern:

Be it known that I, DAISY DEARMAN, a British subject, and a citizen of the Commonwealth of Australia, residing at Paris, France, have invented a new, original Design for Ornament for Box or Similar Article, of which the following is a specification, reference being had to the accompanying drawing, forming part thereof.

The figure is a front view of the box showing my new and original design.

The pen strokes on the side of the head represent fluffy, silky hair expanding from under the cap.

I claim:

The ornamental design for a box or similar article, substantially as shown.
